UNITED STATES PATENT OFFICE.

FRANK L. LOWE, OF ORTING, WASHINGTON.

DESIGN FOR A SHAFT-IRON.

SPECIFICATION forming part of Design No. 31,149, dated July 4, 1899.

Application filed June 6, 1899. Serial No. 719,611. Term of patent 14 years.

To all whom it may concern:

Be it known that I, FRANK L. LOWE, a citizen of the United States, residing at Orting, in the county of Pierce and State of Washington, have invented and produced a new and original Design for a Buggy-Holddback Shaft-Iron, of which the following is a specification.

The invention relates to a new and original design for shaft-irons for holdback-straps; and it has for its object to provide a design of this character which will be both ornamental and useful.

The essential feature of the design resides in a shaft-iron provided at its top with a semicircular loop and having a plate or body presenting an inner concave face and an outer convex face.

A minor feature of the design resides in the plate having rounded terminals and provided between the ends of the semicircular loop with a straight flat edge.

In the drawings, Figure 1 is a perspective view of a shaft-iron, showing my new and original design. Fig. 2 is an elevation of the

same, showing the outer face thereof. Fig. 3 25 is a vertical sectional view.

Referring to the drawings, 1 designates a semicircular bar, circular in cross-section and arranged at one side or edge of a plate or body 2, and the latter has its ends 3 rounded. This 30 plate or body, which is arranged beneath the curved loop-bar 1, presents an inner concave face 4, and it has an outer convex face 5. The upper edge of the plate or body is straight and flat between the ends of the curved loop-bar 35 1, and the plate or body tapers in thickness from the edge 6 to its bottom and ends.

What is claimed is—

The design for a shaft-iron herein shown and described.

In testimony that I claim the foregoing as my own I have hereto affixed my signature in the presence of two witnesses.

FRANK L. LOWE.

Witnesses:

MYRA J. ROWE,
P. T. ROWE.
